UNITED STATES PATENT OFFICE

2,685,962

WARDROBE CONTAINER

Joseph S. Druth, Oak Park, Ill., assignor to Chippewa Paper Products Company, Inc., Chicago, Ill.

Application August 4, 1952, Serial No. 302,534

1 Claim. (Cl. 206—7)

1

This invention relates to a corrugated board wardrobe.

An object of this invention is to provide a corrugated board wardrobe which may be collapsed when not in use so that the wardrobe will not occupy undue space, and the wardrobe may be quickly assembled and set up.

Another object of this invention is to provide a wardrobe which is designed particularly for use in storing clothes in warehouses or the like, so that individual containers may be provided for each group of clothing.

A further object of this invention is to provide a wardrobe which is formed out of corrugated board and includes an inner wooden frame which will support relatively heavy articles and will relieve the outer shell from any strain.

A further object of this invention is to provide a wardrobe which includes a garment hanger bar and means for clamping garment hangers on said bar whereby the hangers will be held against shifting.

With the above and other objects in view, my invention consists in the arrangement, combination and details of construction disclosed in the drawings and specification, and then more particularly pointed out in the appended claim.

In the drawings:

Figure 1 is an exploded perspective view of the inner elements of a wardrobe constructed according to an embodiment of this invention.

Figure 2 is a vertical section of the wardrobe with the outer casing mounted on the inner casing.

Figure 3 is a fragmentary sectional view taken on the line 3—3 of Figure 2.

Figure 4 is a fragmentary sectional view taken on the line 4—4 of Figure 2.

Referring to the drawings and first to Figure 1, the numeral 10 designates generally a lower inner housing which is formed of front and rear walls 11 and 12 and opposite side walls 13 and 14. The upper end of the lower housing 10 is open and a lower end is closed by means of inner bottom flaps 15 and 16 and outer bottom flaps 17 and 18. A skeleton inner frame structure generally indicated at 19 is adapted to be disposed within the inner housing member 10 and is of a height to project a slight distance above the upper edge of the inner member 10.

The frame structure 19 is formed of oppositely disposed frame members 20 which are formed of vertical outer bars 21 and 22, an inner vertical bar 23, and upper and lower connecting bars 24 and 25. A rectangular frame bracing and cover-

2

ing sheet 26, which is formed of corrugated material, is secured to the inner face of each frame member 20, being secured thereto as by staples or other suitable fastening means.

5 The upper bar 24 of each frame member is provided with an opening 27, and a round connecting bar 28 is adapted to be seated within the openings 27. A lower round connecting bar 29 is mounted in openings 30, which are formed in the lower bar 25. The upper bar 28 forms a hanger bar and is secured in the opening 27 by means of a nail or other securing means 31. The lower bar 29 is secured in the lower bar 25 by means of nails or other fastening means 32.

The hanger bar 28 is adapted to have garment hangers 33 mounted thereon, and the hooks of the hangers 33 are adapted to be clamped to the bar 28 by means of a clamping bar 34. The clamping bar 34 extends between the upper frame members 24 and a pair of bolts 35 is extended through bar 34 and through bar 28. A wing nut 36 is threaded on each bolt 35 on the lower side of bar 28 so that bar 34 will be tightly clamped relative to bar 28 and the hooks of the hangers 33. Clamping bar 34 holds the hangers 33 against sliding movement along the bar 28 and also holds the hangers from slipping off of the bar 28 in the event the wardrobe is turned sidewise or upended.

30 A cap member generally designated as 37 is adapted to telescope over the projecting portion of the frame structure 19 and is formed of front and rear corrugated walls 38 and 39, opposite side walls 40 and 41, and a top wall structure which is formed of inwardly projecting side flaps 42 and front and rear upper flaps 43 and 44. The flaps 17 and 18, which form the outer bottom for the lower housing member 10, may be secured together by a tape or the like, and the upper flaps 43 and 44 may also be secured together along their inner meeting edges by means of an adhesive tape or other suitable fastening means.

The inner wardrobe structure hereinbefore described is adapted to be contained within an outer container embodying a lower housing 45 and a telescoping cap or upper housing member 46. The upper housing member or cap 46 is adapted to telescope over cap 37, and lower edges of the cap 46 are secured to the bottom member 45 by means of an adhesive tape 47 or the like.

The wardrobe structure shown in Figure 1 may, when not in use, be collapsed to flat form and initially the connecting bars 28 and 29 will be free from the side frame members 20. When 55 it is desired to set up the wardrobe structure, the

inner frame structure 19, which forms a rigid supporting frame for the wardrobe, may be set up by inserting the bars 28 and 29 in the openings 27 and 30 of the side frame members 20.

After the desired garment hangers 33 have been mounted on the upper hanger bar 28, the inner cap 37 may be telescoped over the projecting portion of the frame structure 19, and the cap 37 will also partly telescope over the lower housing member or container 10, as shown in Figure 2.

The outer container or enclosure for the wardrobe may then be telescoped over the inner wardrobe structure by placing the lower member 10 into the lower member 45 and extending the cap 46 over the cap 37 and partly over the lower enclosure or container 45. The wardrobe hereinbefore described is adapted to be formed out of corrugated board and will provide a sealed housing or wardrobe for receiving clothing which may be shipped or clothing which is placed in a warehouse or other storage.

This wardrobe structure will provide a very convenient means for hanging garments without wrinkling the garments, and it will be understood that by sealing the wardrobe structure, a disinfectant may be placed within the inner structure so that the garments within the wardrobe will not be damaged by moths or other insects.

I do not mean to confine myself to the exact details of construction herein disclosed, but claim all variations falling within the purview of the appended claim.

What is claimed is:

A container comprising an elongated outer lower housing having a substantially rectangular transverse cross-sectional configuration and having opposed open and closed ends, an inner lower housing having a substantially rectangular configuration and having a pair of opposed open and closed ends, said inner lower housing being dis-

posed within said lower outer housing with the said closed ends in juxtaposition, said inner lower housing having a greater elongation than said outer lower housing and projecting therebeyond, a pair of substantially rectangular frame members adapted respectively for facial engagement with a pair of oppositely disposed side walls of said inner lower housing, said frame members being elongated to project beyond the upper end of said inner lower housing, upper and lower spacer bars connected to and supported between the upper and lower ends of said frame members, an upper inner housing having a substantially rectangular configuration in cross-section and having a pair of opposed open and closed ends, said upper inner housing encompassing the exposed outer sides of the projecting ends of said frame members with said closed end thereof abutting against the ends of said frame members and its open end telescopically engaging around the open end of said inner lower housing, and an elongated outer upper housing having a substantially rectangular transverse cross-sectional configuration and opposed open and closed ends, said outer upper housing enveloping said inner upper housing with the closed ends of said outer and inner upper housings in juxtaposition, said outer upper housing being elongated and projecting beyond said open end of said inner upper housing for telescopic engagement about said open end of said lower outer housing.
